Primary Examiner — Catherine S Posthauer*Assistant Examiner* — Joan E. Diehl(74) *Attorney, Agent, or Firm* — Denise D. Deppe(57) **CLAIM**

The ornamental design for an extended sheet, as shown and described.

DESCRIPTION

FIG. 1 is a top perspective view of an extended sheet showing the new design;

FIG. 2 is a front view thereof;

FIG. 3 is a back view thereof;

FIG. 4 is left side view thereof;

FIG. 5 is a right side view thereof;

FIG. 6 is top view thereof; and,

FIG. 7 is a bottom view thereof.

1 Claim, 5 Drawing Sheets(56)
